UNITED STATES PATENT OFFICE.

WILLIAM L. CALDWELL, OF CANTON, OHIO, ASSIGNOR TO THE BERGER MANUFACTURING COMPANY, OF CANTON, OHIO, A CORPORATION OF OHIO.

BUILDING-SHEET.

No. 851,343.

Specification of Letters Patent.

Patented April 23, 1907.

Application filed November 10, 1906. Serial No. 342,765.

To all whom it may concern:

Be it known that I, WILLIAM L. CALDWELL, a citizen of the United States, residing at Canton, in the county of Stark and State of Ohio, have invented certain new and useful Improvements in Building-Sheets; and I do hereby declare that the following is a full, clear, and exact description of the same, reference being had to the annexed drawing, making a part of this specification, and to the numerals and figures of reference marked thereon, in which—

Figure 1 is a perspective view of the sheet. Fig. 2 is a view showing the lined side of the sheet. Fig. 3 is a section on line 1—1, Fig. 1. Fig. 4 is a sectional view showing a modification.

The present invention has relation to building sheets, especially designed for roofing, siding and for such other purposes as may be or are necessary in the construction of buildings.

Similar numerals of reference indicate corresponding parts in all the figures of the drawing.

In the accompanying drawing, 1 represents the sheet, which may be formed of any desired size and of metal such as is commonly used for the purpose above pointed out. The sheet 1 is provided with any desired number of ridges 2, which ridges are produced by bending the body of the sheet at an angle to the remaining plain portion of the sheet. Upon one face of the sheet is located a sheet of non-metallic lining material 3, which material is originally placed upon the face of the sheet and said non-metallic material bent or folded with the angled bends or folds of the sheet, said folded portions of the non-metallic sheet located and bound or locked in the folds of the metallic sheet, thereby securely connecting the lining to the metallic sheet without the absolute necessity of using any adhesive substance to connect the non-metallic and metallic sheets together. However in some instances it may be desirable to use an adhesive substance in addition to the clamping effect produced by folding the non-metallic and metallic sheets as shown. In some instances it is desirable to employ wires 4 and bend the non-metallic and metallic

sheets around and upon said wires, which wires when imbedded as shown will prevent the non-metallic sheets from becoming detached by any pulling strain or by gravity. 55

In Fig. 4 I have illustrated the non-metallic and metallic sheets connected together by folds or ribs without the use of the binding wires or in other words the non-metallic sheet is clamped between the angled portions 60 of the metallic sheet 1, which folds constitute the ribs 2.

I have learned from experience that when adhesive substance is exclusively employed to connect the non-metallic and metallic 65 sheets together that there is a liability of the non-metallic sheets or lining to become detached from the metallic sheets but by my improved method the liability of the non-metallic or lining sheet to become detached is 70 avoided.

It will be understood that by forming the ribs or bends a double purpose is brought about, first as above stated to bind the lining and second to stiffen the sheet and to prevent 75 any sagging or bending of the sheet between the supports of the sheet.

Having fully described my invention what I claim as new and desire to secure by Letters Patent, is—

1. An improved building sheet consisting of metallic and non-metallic members, the metallic member provided with folds or ridges bent from the body of the metallic member and the non-metallic member located upon one face of the metallic member, the folds of the non-metallic member bound in the folds of the metallic member, substantially as and for the purpose specified. 85

2. An improved building sheet consisting 90 of metallic and non-metallic members, the non-metallic and metallic members provided with folds or ridges, the folds of the non-metallic member locked in the folds of the metallic member, substantially as and for the purpose specified. 95

3. A building sheet consisting of metallic and non-metallic members, said non-metallic and metallic members provided with ridges or folds, the non-metallic and metallic folds 100 located around binding wires, substantially as and for the purpose specified.

4. A building sheet consisting of metallic and non-metallic members, said non-metallic and metallic members provided with ridges or folds, the non-metallic and metallic 5 folds located around binding wires, and the non-metallic folded or ridged portions located upon the wires, substantially as and for the purpose specified.

In testimony that I claim the above, I have hereunto subscribed my name in the presence of two witnesses.

WILLIAM L. CALDWELL.
